Be it known that I, NICHOLAS WITSCH, a citizen of the United States, residing at Jersey City, in the county of Hudson and State 5 of New Jersey, have invented and produced a new and original Design for an Ornamental Print or Pattern for Cigar-Boxes; and I do hereby declare the following to be a full, clear, and exact description of the same, reference 10 being had to the accompanying drawing, forming a part thereof—

The design is placed upon a cigar-box, as shown in the drawing.

The design consists of three panels arranged side by side, having highly ornamented borders entwined with a flowering
